UNITED STATES PATENT OFFICE.

DANIEL B. LUTEN, OF INDIANAPOLIS, INDIANA.

CONCRETE OR SIMILAR ARCH.

No. 853,183.

Specification of Letters Patent.

Patented May 7, 1907.

Application filed June 24, 1905. Serial No. 266,818.

To all whom it may concern:

Be it known that I, DANIEL B. LUTEN, a citizen of the United States, residing at Indianapolis, in the county of Marion and State of Indiana, have invented new and useful Improvements in Concrete or Similar Arches, of which the following is a full, clear, concise, and exact description, reference being had to the accompanying drawing, forming a part of this specification.

My invention relates to improvements in concrete or similar arches, and particularly to that class of such arches as are re-enforced in the regions most liable to failure.

The invention has for its objects generally speaking, the provision of arches of the class referred to; that are of improved design, economical to erect, capable of withstanding comparatively heavy loads, and that are of graceful outline and pleasing appearance.

In the accompanying drawings, Figure 1 is a longitudinal sectional view in elevation of a concrete or similar arch showing re-enforcing tension members arranged according to certain methods of the present invention, said members being embedded in the material of the arch; Fig. 2 is a similar view of an arch showing different arrangements of the re-enforcing members; Fig. 3 is a sectional elevation of an arch having re-enforcing ribs applied to the arch rib or ring, said ribs being re-enforced, if desired, in accordance with the various forms of the present invention; Fig. 4 is a similar view of still another form of arch, and, Fig. 5 is a cross section of Fig. 4 through the center of the arch.

Referring to Fig. 1, the arch rib or ring 2 supported at its ends upon the abutments 3 is preferably composed of concrete or similar material. Under the ordinary and usual loading of such an arch, tension is produced in the intrados at the crown and in the extrados over the haunches. In view of the fact that concrete is incapable of withstanding any great amount of tension these regions are re-enforced by means of the usual metallic tension members capable of successfully resisting tension such as small steel rods, cables, chains, wire netting or thin or expanded sheet metal. Thus, at the crown, the tension member or members 4 are located near the intrados and the corresponding members 5 and 6 at the right and left haunches near the extrados. These tension

members consist of short lengths of steel rod 55 or other suitable cross section capable of resisting tension placed in the alternate regions of tension in the arch ring. These short rods, as they may be termed, are connected together in some manner adjacent the regions of no tension or of minimum bending moment and maximum shear, either by merely overlapping the same in such regions as indicated in other figures of the drawing by welding them together, hooking them 65 around each other, or otherwise splicing the meeting ends as indicated at 7, 8 and 9 in Fig. 1, or the two ends of the members 4 and 5 may be prolonged and then be bent across the arch rib and hooked around the opposite 70 rod as indicated at 10, and 11 at the right in Fig. 1. In case tension rods are employed they are spaced across the arch at suitable intervals, as for instance, every two or three feet, and cross the arch rib at various longitudinal points as indicated at the left in Fig. 1. While theoretically the weld or connection of the external and internal rods should be at the middle of the crossing of the rib as shown at 8, it facilitates buying, handling 75 and construction to have all of the rods of stock lengths and such lengths may be employed by shifting the said connections slightly to one side or the other as indicated at 7 and 9. Since there is no point of maximum tension near the point of crossing, and if the weld or junction of the rods develops as much as fifty per cent of the rod strength, the joint is safe even at a considerable distance from the point of change of moment, 80 85 The crossing of the rods at the different places in the rib provides a plurality of shearing members in the region of maximum shear, and, of course, of minimum bending moment. In the arrangement shown at the 90 right in this figure, the rods 4 and 5 are in the same vertical plane and since they pass each other and cross the rib at different points, the arch ring is re-enforced throughout the doubtful region along both faces and 95 with a plurality of members through the region of maximum shear. This construction and arrangement of short sections of tension members suitably overlapping and spliced together if desired, is of advantage particularly in a long arch where a continuous bar from end to end would require several welds 100 and is unwieldy and more or less difficult to 105

handle during the erection of the arch. The present method divides such bar or rods into three parts, thus rendering more easily handled, while the arch is re-enforced as effectively against tensile stresses as in the case of the continuous bars and in addition is provided with re-enforcement at both intrados and extrados along the doubtful region. There is also furnished at least two shearing members at the region of minimum moment and maximum shear. It will be understood that any method of connecting the tension members or of splicing them may be employed, and so far as some features of the invention are concerned, they may be merely overlapped in adjacent regions, the ends of such overlapping rods being preferably bent at an angle to afford secure anchorage. The outer ends of the rods 5 and 6 through the haunches are preferably extended into the abutments and along the outer edge, and are bent around suitable transverse bars or rods 12 embedded in the material of the arch to afford a secure anchorage for said rods.

In Fig. 2 the same style of arch ring is shown but the tension member embedded at the crown near the intrados consists of a rod or bar 13 having transverse members attached thereto and extending up into the arch rib, the members 14 at the center being at about right angles to the bar 13 while those such as 15 near the ends of the rods are at about forty-five degrees to the main rod. The latter members are located in the regions of no bending moment and of maximum shear and their arrangement at a forty-five degree angle successfully resists and re-enforces against such shear. At the center of the arch, such transverse members tend to prevent the rod 13 from pulling out of the lower face of the concrete when they tend to straighten under tension. It is obvious that the ends of these transverse members may be bent at an angle as indicated at 16 if desired to more effectively resist this tendency of the bar 13 to pull out of and rupture the lower face of the arch. At the left of this figure this tension member 17 extends over the haunches near the external face of the rib in which it is preferably anchored at its outer end is bent across the rib and hooked as at 18 to the bar 13. At other vertical planes such bars may cross at different points or not as desired. The arrangement shown for such external rods is preferred. At the right in this figure is shown embedded in the tension region of the extrados, a bar 19 similar to the bar 13 at the crown in that it is provided with transverse members 20 attached thereto and extending into the arch rib. The members 20 at the inner end of said bar 19 overlap and interlace the corresponding members 15 upon the bar 13 and may be tied together in any preferred manner if desired. These overlapping members and ends are in the region of

minimum bending moment and maximum shear. Such transverse members attached to the bar 19 effectually anchor the main bar so that other anchorage is unnecessary, although it may be employed if desired. By attaching the bar 17 at the left to the inner bar, said outer bar is held in place while the concrete of the arch ring is being deposited.

In Fig. 3, I have shown an arch with a rib 21 designed to resist the thrust mainly while the bending moments are resisted by projecting ribs 22 on the exterior and 23 upon the interior throughout the tensional regions; and these ribs preferably contain embedded re-enforcing members designed to resist tension and which are thus so far displaced from the central axis of the arch ring as to give them greater moment to resist. Thus the rib 21 which is shown in section is comparatively light, while the ribs 22 and 23 upon the opposite sides of the same are projected outside of the faces of said rib, and for the sake of economy of material are preferably spaced transversely at about two or three feet apart. The re-enforcement applied to this form of arch may obviously be of any desired type, that is, the said members may be continuous, discontinuous or otherwise arranged, but I have shown such re-enforcement at the left consisting of the rods 24 suitably anchored at their outer ends in the material of the arch rib and at their inner ends crossing the arch ring in the region of no bending moment and hooking around or otherwise attaching to the rod in the rib 23, as at 25. The corresponding rods 26 in the rib 23 likewise extend across the arch rib preferably at a different longitudinal point so as to give another shearing member in the region of maximum shear and are attached as at 27 to the rod 24, a convenient method of forming said attachment being merely to hook the end of the rod around the opposite rod in the same vertical plane. As indicated at the right in this same figure, the bar 26 and the corresponding bar 28 in the external rib may be provided with transverse prongs or members similar to those indicated in Fig. 2, which overlap and interlace in the region of maximum shear and of no bending moment, and which also project into the material of the rib itself and serve to bond such projecting ribs to the arch rib. By the above described arrangement of the tension rods they may be placed at a greater distance from the central axis of the arch than is usual, and therefore may be smaller so that less steel is required for reinforcement and a less amount of concrete or similar material is required for the body of the arch. An additional advantage in this latter structure resides in the fact that the arch can be built to the theoretical form required while the projecting ribs may serve as a screen to give the arch a semi-circular or elliptical appearance as is indicated in the

figure at the left. Thus at the right the usual abutment 29 is provided, but at the left the arch rib is designed for strength with economy of material and is extended to a suitable footing 30 while the same external appearance is imparted to this end of the structure as that at the right by means of the internal rib 31 following the general curvature of the inner face of the other end of the arch. Thus the semi-circular or elliptical appearance is imparted to the structure as a whole. The latter rib is indicated as re-enforced by a tension member 32 embedded therein and having its lower end anchored in the footing 30, and its upper end extending up across the arch body and into the projecting rib 22 where it is hooked around the rod 24 therein. Another tension member 33 may extend along the inner face of the arch ring. The projecting ribs may be placed closer together or farther apart than stated and any rib may be omitted by replacing its tension member with a heavier member embedded in the body of the rib itself. The tension ribs also may have a separate re-enforcement ending at the edges of the tension regions or extending far enough into the compression regions to secure anchorage.

In Fig. 4 an arch is shown in which the rib is designed for efficiency of form, regardless of appearance, while the carrying ribs are so placed as to give the usual form and appearance to the arch, in this case a semi-circular appearance with vertical bench walls. These ribs may be employed as described in connection with Fig. 3 for the purpose of carrying reinforcing tension members. In case these ribs are employed only for the sake of appearance, they may be omitted except at the two faces or ends of the arch. In this figure the rib is indicated at 34 and terminates at its two ends in footings 35, this section being especially designed for efficiency. Upon the interior at the crown, ribs 36 are provided, and near the footings the ribs 37 are added. Corresponding ribs 38 are provided upon the haunches, the form thus imparted to the combined structure being that of a semi-circular arch supported upon bench walls. These ribs may be placed at the desired intervals throughout the structure as indicated in Fig. 5 but particularly in the case of the bench wall ribs may be omitted only when used for appearance except at the faces. Reinforcing members of any type or those particularly described herein may be provided in said projecting ribs, the rods or members 39 being shown continuous throughout the alternate tensional regions, while the members 40 are of the type provided with attached prongs or transverse members. At 41, the rods are shown crossing the arch at different places and hooked around each other at their ends. The rods 41 are shown passing across the lower end of the rib on the

right, thence along the inner face of the bench wall rib and curved at the ends to secure anchorage. At the left a rod 43 passes along the inner face of the rib 37 and then crosses the arch and hooks around the adjacent rod 39 at a point 44. One of the rods 39 is shown crossing the rib and hooking around the rod 43 at the point 45. Any arrangement of reinforcing members may obviously be employed. By extending the bench wall ribs deep enough they may act as protection against scouring under the abutments.

In all these figures non-continuous rods or members as distinguished from continuous rods or members extending through the alternate tensional regions are shown, this feature being of considerable practical value in the purchase of such material in the open market, and in handling and using the same for its intended purchase.

While I have thus shown and described certain specific embodiments of my invention, I do not wish to be limited thereto in all respects as various changes, alterations and modifications may be made therein without departing from the scope or principle of the same. For example, an arch may be so loaded that the regions of tension would occur on the outside at the crown and at the intrados at the haunches; or so that there would be five or more regions of tension alternately on opposite sides of the arch rib. I claim broadly therefore, the arrangement of reinforcing rods and ribs along the regions of tension with the rods crossing the rib and joining at the regions between. I claim the arrangement of rods and ribs on alternately opposite sides of an arch rib, the rods crossing the rib and joining the alternate rods between the regions of tension.

Having thus described my invention what I claim as new and desire to secure by Letters Patent, is:

1. An arch of concrete or other material having reinforcing members embedded near intrados and extrados alternately, the ends of said members overlapping and extending across the arch rib at the shearing regions.
2. An arch of concrete or other material having reinforcing members passing through the tensional regions, the ends of said members being bent across the arch rib and overlapping at the shearing regions.
3. An arch of concrete or other material having reinforcing members passing through the tensional regions, the ends of said members being bent across the arch rib at the shearing regions and attached to one another.
4. An arch of concrete or other material having reinforcing members embedded near the intrados and extrados alternately, the ends of said members overlapping and crossing the arch rib at the shearing regions, but displaced longitudinally with respect to one another.

5. An arch having reinforcing members embedded near alternate intrados and extrados only, but with ends overlapping and extending across the arch ring at points alternately displaced. 16. An arch of concrete with the exposed faces of the arch presenting a different curvature from the body of the arch. 75
6. A concrete arch having reinforcing tension members along alternately opposite portions only of intrados and extrados, such tension members having transverse members extending transversely of the arch rib. 17. An arch of concrete having ribs projecting from the intrados near the ends of the barrel and at a different curvature from that of the barrel. 80
7. A concrete arch having a reinforcing tension member along a part only of the intrados, said member having attached thereto diverging members arranged at an angle thereto and extending into the arch, and other reinforcing members near the extrados at alternately opposite points. 18. A concrete bridge with an arched rib at the end of different form from the main portion of the bridge. 85
8. A concrete arch rib having reinforcing tension members along a portion of the intrados, with other diverging members attached to the reinforcing members and extending across the arched rib, and other tension members embedded near alternately opposite portions of extrados only, but with the ends overlapping the ends of the intrados tension members and crossing the arch rib at points longitudinally displaced with respect to one another. 19. A concrete bridge with ribs projecting alternately above and below a continuous transverse member, and reinforcing members embedded in said ribs. 90
9. A concrete arch having reinforcing tension members extending along the intrados and the extrados in the tensional regions, the members in the intrados having diverging members attached thereto and extending into the arch rib, the ends of the members in the extrados crossing the rib to join the intrados members. 20. A bridge of concrete or similar material with ribs projecting above and below, and with tension members having shearing members attached thereto embedded in the lower ribs. 95
10. An arch or bridge reinforced with embedded tension members said members each having a plurality of diverging shearing members attached near one end, said tension members being arranged alternately to provide a materially greater reinforcement near one face than near the immediately opposite face. 21. A bridge of concrete or the like with ribs projecting both above and below and with a roadway between the upper ribs and having reinforcing members in the lower ribs. 100
11. An arch having projecting ribs extending from the arch ring back of the abutments. 22. A bridge of concrete or similar material reinforced with tension members extending through the tensional regions with substantially parallel endings in the shearing regions. 105
12. A concrete bridge with ribs projecting alternately above and below a continuous transverse member. 23. A concrete bridge with ribbed and reinforced abutments. 110
13. An arch having projecting ribs containing embedded tension members alternately on opposite sides of the arch ribs, said tension members being continuous through the arch from rib to rib. 24. An arch of concrete with abutments reinforced with vertical ribs. 115
14. An arch having a barrel or ring constructed of the desired form, said barrel or ring being provided with end flanges or projecting ribs to give the desired appearance to the end of the arch. 25. An arch of concrete with ribs projecting from the abutments. 120
15. An arch having its ring or barrel constructed for efficiency without regard to appearance, said ring or barrel being provided with end flanges or projecting ribs to give the structure the desired appearance at the ends. 26. A concrete arch having projecting ribs alternating longitudinally on opposite sides and tension members embedded in the ribs. 125
16. An arch with embedded reinforcing members on opposite sides of a region of minimum bending moment welded or spliced to one another across the region of minimum bending moment. 27. A concrete arch having projecting ribs alternating longitudinally on opposite sides. 130
17. An arch with embedded tension members embedded on opposite sides of a region of minimum bending moment with splices between opposite members near regions of minimum bending moment. 28. A concrete bridge with tension members embedded on opposite sides of a region of minimum bending moments with splices between opposite members near regions of minimum bending moment. 135
18. A concrete arch with tension members embedded crossing the arch rib near the points of minimum bending moment, said tension members being welded, spliced or joined near the points of crossing to form a continuous member following both surfaces of the arch rib. 29. An arch with embedded tension members passing through regions of tension and welded or spliced between the regions of tension to form a member continuous between the regions of tension. 140
30. An arch of concrete or similar material with a metal tension member embedded near the extrados and spliced or welded near a region of minimum bending moment, to a 145

metal tension member embedded near the intrados.

33. A concrete arch having an external rib projecting above the extrados and back of the abutment and a tension member passing from the arch into the projecting rib.

34. A concrete bridge having a reinforced rib projecting back of the body of the abutment force.

10 35. An arch of concrete or similar ma-

terial having a reinforced rib extending back of the abutment, said reinforcement continuing into and through the arch ring.

In witness whereof, I have hereunto subscribed my name in the presence of two witnesses.

DANIEL B. LUTEN.
